AUDIO AMPLIFYING TRANSFORMER AND
STATIC ELIMINATOR

Anton Straka, Chicago, Ill.

Application November 11, 1931, Serial No. 574,399

5 Claims. (Cl. 250—20)

This invention relates to radio transmission and has special reference to an audio-amplifying transformer and static eliminator.

One important object of the invention is to improve the general construction of devices of this character.

A second important object of the invention is to provide a novel device of this class wherein a thin air gap is employed in the primary circuit to produce an ionized field which inductively affects the secondary circuit to produce a current therein.

A third important object of the invention is to provide a novel device of this character wherein the area of the air gap in the primary circuit may be varied at will.

A fourth important object of the invention is to provide a novel transformer of this class wherein the air gap in the primary circuit is formed by the nesting, one within the other, of a pair of concentric tubes, one or more pairs of such tubes being capable of use in this connection. With the above and other objects in view the invention consists in general of certain novel details of construction and combination of parts hereinafter fully described, illustrated in the accompanying drawing, and specifically claimed.

In the accompanying drawing like characters of reference indicate like parts in the several views, and:—

- 30 Figure 1 is an end elevation of the invention.
Figure 2 is a side elevation thereof.
Figure 3 is a section on the line 3—3 of Figure 2.
Figure 4 is a section on the line 4—4 of Figure 1 with the parts behind the plane of section omitted.

Figure 5 is a schematic diagram of the circuit arrangements herein used.

In the embodiment of the invention as herein illustrated there is provided a pair of spaced heads 10 and 11 which are formed preferably of insulating material. These heads are substantially square and at opposite edges carry guide strips 12. The strips 12 are arranged in spaced pairs and have their adjacent edges undercut as clearly shown in Figures 1 and 3. Sliding between the upper pair of the strips 12 is a guide strip 13 having its edges bevelled to fit the bevelled edges of the strips 12. A similar guide strip 14 is carried between the lower strips 12 and on the under side of this strip 14 is a gear rack 15 wherewith meshes a pinion 16 mounted on a shaft 17 provided with an operating knob or handle 18. This operating means is suitably mounted in the casing used for apparatus of this character, being here shown to indicate a suitable

operating means for the device. The strips or slides 13 and 14 carry a third insulating head 18 which may thus be moved toward and from the head 11.

Supported in the heads 10 and 11 in a circular series about the centers of these heads are spaced metallic tubes 19, preferably open at both ends. These tubes are connected in continuous series by a wire or other conductor 20 which in turn is connected to a suitable building post 21 by a wire 22. The tubes 19 are thus connected in multiple to the post which forms the connection for one terminal 23 of the input or primary circuit. Tubes 24 are carried by the head 18 and are arranged in axial alignment with the respective tubes 19, the tubes 24 having an external diameter slightly less than the internal diameter of the tubes 19 and projecting into said tubes 19 to leave thin air gaps 25. The tubes 24 are connected, like the tubes 19, in continuous series by a wire 26 which is in turn connected by a wire 27 with a binding post 28 carried by the head 18. The binding post 28 forms the connection for the remaining terminal 29 of the input or primary circuit.

As thus constructed the tubes 19 form a frame on which is wound the secondary winding 30 formed of fine insulated wire and having one end of the winding connected to a binding post 31 and its other end connected to a binding post 32, these binding posts being here shown as mounted on the head 10 and forming connections for the respective terminals 33 and 34 of the output or secondary circuit.

Obviously, since it has been above set forth that the terminals 23 and 29 are the input terminals and the terminals 33 and 34 are the output terminals, the device, when used in a radio receiving set will have the input terminals connected, as in all other transformers thus used, to one tube and the output terminals connected to the next succeeding tube. In such case, as well understood by those skilled in the art, the present device is to be connected in parallel to a resistance 35 that is included in the plate circuit. The output terminals are connected respectively to the filament and grid of the second tube. Under such conditions it is found, in actual practice, that the static effects are greatly reduced and it is believed that this is due to the ionized field between the inner and outer tubes.

Under these conditions the primary current produces an ionized field due to the gaps 25 and this causes the production of a secondary current in the secondary winding 30, the primary cur-

rent being of relatively low and the secondary current being of relatively high voltage. Moreover, by moving the tubes 24 in or out of the tubes 19 telescopically, the areas of the air gaps 5 between the tubes 24 and 19 can be increased or diminished at will and thereby the amplification can be regulated as desired.

There has thus been provided a simple and efficient device of the kind described and for the 10 purpose specified.

It is obvious that changes may be made in the form, construction, and proportions of the invention. It is not, therefore, desired to confine the invention to the exact form herein shown 15 and described but it is desired to include all such as properly come within the scope claimed.

Having thus described the invention, what is claimed, is:—

1. A device of the kind described including a 20 plurality of pairs of tubes, one tube of each pair being telescopically mounted within the other tube of said pair but concentrically spaced therefrom, means to move the inner and outer tubes telescopically with reference to each other, means 25 to connect all of the outer tubes in multiple to a circuit terminal, other means to connect all of the inner tubes in multiple to a second circuit terminal, and a secondary winding of fine wire surrounding the outer tubes.
2. In a device of the kind described, a pair of 30 spaced plates, a series of parallel tubes supported in said plates, a third similar plate movable toward and from one of the pair of plates, a series of tubes carried by the third plate and each 35 projecting telescopically in a respective first tube, the tubes of the second series being concentrically spaced within the tubes of the first series, pairs of spaced guide strips connecting the pair of plates, other guide strips carried by the third plate and slidably fitting between the respective 40 pairs of guide strips, means to connect all of the outer tubes in multiple to a circuit terminal, other means to connect all of the inner tubes in 45 multiple to a second circuit terminal, and a secondary winding of fine wire surrounding the outer tubes.

3. In a device of the kind described, a pair of 30 spaced plates, a third similar plate movable toward and from one of the pair of plates, a series 35 of tubes carried by the third plate and each projecting telescopically in a respective first tube, the tubes of the second series being concentrically spaced within the tubes of the first series, pairs 40 of spaced guide strips connecting the pair of plates, other guide strips carried by the third plate and slidably fitting between the respective 45 pairs of guide strips, a rack on one of the last mentioned guide strips, a pinion meshing with

projecting telescopically in a respective first tube, the tubes of the second series being concentrically spaced within the tubes of the first series, slide- 5 able guide means connecting the third plate with the pair of plates, means to connect all of the outer tubes in a multiple to a circuit terminal, other means to connect all of the inner tubes in multiple to a second circuit terminal, and a secondary winding of fine wire surrounding the outer tubes.

4. In a device of the kind described, a pair of spaced plates, a series of parallel tubes supported in said plates, a third similar plate movable toward and from one of the pair of plates, a series of tubes carried by the third plate and each 15 projecting telescopically in a respective first tube, the tubes of the second series being concentrically spaced within the tubes of the first series, pairs of spaced guide strips connecting the pair of plates, other guide strips carried by the third plate and slidably fitting between the respective 20 pairs of guide strips, means to connect all of the outer tubes in multiple to a circuit terminal, other means to connect all of the inner tubes in 25 multiple to a second circuit terminal, and a secondary winding of fine wire surrounding the outer tubes.

5. In a device of the kind described, a pair of spaced plates, a series of parallel tubes supported in said plates, a third similar plate movable toward and from one of the pair of plates, a series of tubes carried by the third plate and each 30 projecting telescopically in a respective first tube, the tubes of the second series being concentrically spaced within the tubes of the first series, pairs 35 of spaced guide strips connecting the pair of plates, other guide strips carried by the third plate and slidably fitting between the respective pairs of guide strips, a rack on one of the last mentioned guide strips, a pinion meshing with 40 said rack to move the rack inwardly and outwardly, means to connect all of the outer tubes in multiple to a circuit terminal, other means to 45 connect all of the inner tubes in multiple to a second circuit terminal, and a secondary winding of fine wire surrounding the outer tubes.

ANTON STRAKA.
